PROCESS OF EXTRACTING IODIN.

No. 915,959.

Specification of Letters Patent. Patented March 23, 1909.

Application filed May 9, 1906. Serial No. 216,002.

To all whom it may concern:

Be it known that I, ERNEST HERRMANN, a citizen of the Republic of France, residing at 78 Rue d'Anjou, Paris, France, have invented new and useful Improvements in Processes of Extracting Iodin, of which the following is a specification.

This invention relates to a method by means of which iodin can be quickly and economically extracted from liquids containing iodids, iodates or organic ioduretted compounds. These liquids may be obtained by the exhaustion of fresh sea-weed, dry sea-weed, sea-weed ash or ioduretted substances of any kind. This exhaustion may be effected in any manner, according to processes already known. If it be desired to proceed quickly, methodical exhaustion with hot water (system of diffusers in sugar works) is advisable. If cold water be employed it is advisable in the case of fresh sea-weed to destroy the cells, in order that the sea-weed may more easily yield its ioduretted compounds. The treatment is either effected with a lime-milk, according to already known processes, or with an acid diluted to 2 to 3 per thousand, also according to already known processes. Sea-water may indeed be employed. It is only necessary to put about 2 grams more lime per liter in the milk of lime which may contain in that case from 5 to 7 per thousand of lime, so as to compensate the loss of lime due to the decomposition of the chlorid of magnesium which gives chlorid of calcium and insoluble magnesia which does no harm. Thus liquids are obtained which according to treatment and origin are richer in ioduretted compounds to the extent of 300 to 1000 grams of iodin per cubic meter. These liquids are then decanted, if necessary, or even filtered; they are then conveyed to wooden vats of medium size, in which stirring is easily effected, and the iodin set free by one of the known means, sulfuric acid or nitrate of soda for example. The ioduretted compounds are thus decomposed and the iodin set free. 60 liters (or approximately) of pure vaseline oil per cubic meter of liquid are then added and the liquid is agitated for a certain time so as to bring the vaseline oil well in contact with the liquid. The oil assimilates the free iodin and collects very rapidly on the surface.

The process is carried out methodically. The pure vaseline oil first treats liquids par-

tially exhausted and poor in iodin, then passes over liquid already once exhausted and finally over a fresh liquid. Thus 95% of iodin is carried off with about 60 liters of vaseline oil per cubic meter of liquid. This 60 vaseline oil thus enriched with iodin, is poured into a stoneware or wooden receptacle and heated directly by a current of steam. This receptacle communicates with another similar receptacle through a porcelain or glass refrigerator, the latter if necessary being multitudinous in order to effect adequate cooling.

The steam begins by heating the oil and the first receptacle must be rather large in order to contain the vapor condensed by this operation. Then, when the vaseline oil is hot, the steam carries off the iodin which is sublimated and becomes condensed in the refrigerator. Owing to the action of the 75 steam the refrigerator does not become stopped. The second receptacle on the other side of the refrigerator receives the condensed steam and particles of iodin carried along in the water. When the vaseline oil 80 has thus been deprived of its iodin, it is cooled and is employed again for treating liquids already partially exhausted. The vaseline oil may also be deprived of its iodin, if so preferred, by being directly heated or by 85 being acted on by a current of hot air or of an inert gas.

If it be desired to proceed more quickly with the removal of the iodin from the vaseline oil so that a smaller quantity of vaseline 90 oil will be required for the whole treatment, the iodin may be exhausted from the vaseline oil itself by stirring the oil with a liquid capable of forming a combination with the iodin. This result may be obtained very 95 quickly with a solution of potash or of soda, but a certain time is required for decanting. The solution of sulfite of soda, while not taking more time to absorb the iodin, allows of very quick decanting.

The operation may proceed as follows:— To 600 parts of ioduretted vaseline oil, 1000 parts of water containing an excess of sulfite are added, stirring being carried on until the color due to the iodin has disappeared. The 105 vaseline is decanted, removed and replaced by an equal quantity of ioduretted vaseline oil. Thus with the same quantity of liquid, to which when necessary sulfite is again added, it is possible to exhaust 15 to 20 volumes 110

of vaseline oil, thus enabling a highly concentrated iodid liquor to be obtained. The iodin of these concentrated liquors is set free by the known means, nitrites or chlorates, and it is separated by being drawn off by means of steam, by the process already described in relation to ioduretted vaseline oil, or it may be re-collected by decanting when it is precipitated.

10 The pure vaseline oil which is used in the process is obtained from the petroleum of Galicia (Austria); it constitutes a neutral uncolored liquid which distils only at a temperature above 350 degrees Celsius (660° F.). 15 This vaseline oil appertains to the chemical group of paraffins; it is not oxidized by contact with air, and it is not affected by the presence of concentrated acids.

19 The employment of vaseline oil insures the following advantages: The oil does not evaporate and does not ignite like benzene, petroleum or the like; it floats on the surface, thus enabling more or less clear liquids to be employed (this being impossible with solvents heavier than water, such as carbon bisulfid, chloroform or tetrachlorid of carbon), without washing and without subsequent treatment; it distils at about 345 degrees centigrade, thus enabling steam to be employed, as it does not emit any vapor before reaching its point of distillation. Finally the chemical group to which it belongs—the paraffins—are insensible to reagents and non-oxidizable in the air and thus can be employed indefinitely.

An apparatus for carrying out the process is shown in sectional elevation in the accompanying drawings.

In this Figure 1 is a receptacle of wood or other convenient material for containing the liquids from which iodin is to be extracted; 2 is a similar receptacle containing pure vaseline oil; 3 is a wooden vat provided with a stirring apparatus 4 actuated by any well

known means; 5 is a tube or pipe for supplying the liquid contained in the receptacle 1 to the vat 3; 6 is another pipe by means of which the pure vaseline oil contained in the receptacle 2 is discharged to the bottom of the vat 3. The oil enriched with iodin collects on the surface and is discharged continuously by the tube 7, into the stone-ware receptacle 8. 9 is a tube by which a current of steam is introduced directly to the bottom of the said receptacle 8, for heating the vaseline oil enriched with iodin; the outlet of the tube 9 is preferably provided with small holes so as to form a kind of sprayer for the exit of steam. The receptacle 8 communicates with the second receptacle 10 by means of a tube 11, preferably of porcelain or glass for the escape of the steam carrying off the iodin which is sublimated. The refrigeration is obtained by cold water, furnished by a tank 12 which communicates with the refrigerating jacket 13, by means of the pipes 14 and 15, arranged in the manner shown in the drawing for obtaining a continuous flow of cooling water. The arrows in the drawing show the directions in which the fluids move in the different tubes and receptacles.

Having now described my invention, what I claim as new and desire to secure by Letters Patent is:

A process of extracting iodin consisting in first liberating the iodin from iodin lyes, then mixing the iodin liquid with vaseline oil and then obtaining pure iodin directly from the resultant solution by subliming with steam.

In testimony whereof I have signed my name to this specification in the presence of two subscribing witnesses.

ERNEST HERRMANN.
